UNITED STATES PATENT OFFICE.

PAUL WILFRED ENSIGN, OF SOUTH PASADENA, CALIFORNIA, ASSIGNOR TO ENSIGN CARBURETOR COMPANY, OF LOS ANGELES, CALIFORNIA, A CORPORATION OF CALIFORNIA.

CARBURETOR.

Application filed April 13, 1922. Serial No. 552,322.

This application relates to improvements over the invention set forth in the copending application filed by Roy Francis Ensign, November 25, 1919, Serial No. 340,658.

5 This invention relates to improvements in carburetors for internal combustion engines, whereby better and quicker acceleration of internal combustion engines of the automotive type is made possible.

10 An object of this invention is to provide means whereby the idling mixture for such engines may be more perfectly controlled.

An object is to provide by simple means, ample accelerating fuel for such engines, to 15 cause gradual delivery of such accelerating or excess fuel upon opening the throttle from idling position, and also to accumulate accelerating fuel from the main fuel stream upon closing the throttle, and to hold it in 20 readiness for subsequent acceleration.

An object is to provide simple improved means whereby fuel may be drawn from the fuel supply and added to such accumulated fuel, and thence transmitted to the main air 25 stream to keep the engine running during idling.

Another object is to provide means whereby a predetermined quantity of accelerating fuel may be accumulated upon closing the 30 engine throttle.

Another object is to provide simple and more effective means for regulating the idling mixture.

Another object is to facilitate starting the 35 engine when hot without using the starting choke.

Another object is to make possible perfect control of idling mixture and to furnish sustained accelerating fuel for any type of carburetor in which the fuel flows downward 40 from the fuel supply chamber to the main air stream.

Other objects, advantages and features of 45 invention may appear from the accompanying drawing, the subjoined detail description and the appended claims.

The accompanying drawing illustrates the invention.

Figure 1 is a vertical section of a carburetor provided with the improvement. The parts are shown in position for idling, and the liquids are shown in position of rest.

Fig. 2 is an enlarged fragmental axial

section of the carburetor shown in Fig. 1, with the liquids shown in the position assumed during idling operation of the engine. 55

Fig. 3 is a section in the scale of Fig. 2 on irregular line α^3 , Figs. 1 and 2.

The invention is applicable to various types of carburetors of the down flow fuel feed type or those in which the fuel is delivered to the mixture passage at a point below the constant fuel level and in the drawings is shown as applied in a vortex type of carburetor in which the air inlet 1 admits air past the choke valve 2 tangentially into the mixing chamber 3 where it forms the main air stream that receives the fuel delivered from the constant level fuel chamber 4 through fuel orifice 5 into the fuel suction chamber 6 where the fuel overflows through the intake 7 of the fuel passage which comprises a drop pipe 8 where the fuel passes downward toward the mixing chamber 3. 75

In the present invention the fuel passage comprises a reservoir 9 which is positioned above the lower end of and encircles the lower portion of the drop pipe 8 with which it communicates through downwardly extending leads 10 which terminate at the bottom of said reservoir. A separable sleeve 12 mounted on body 11 forms the outer wall of the reservoir and is provided at its top with orifices 13 to permit discharge of the fuel 80 from the reservoir into the main air stream in the mixing chamber 3.

As is common the suction chamber 6 is provided with a restricted air port 14 admitting air into the suction chamber under 90 all conditions of carburetor operation. This air is admitted through the equalizer tube 15 leading from the air inlet 1.

The mixing chamber opens into the mixture passage 16 which is controlled by a 95 throttle 17.

There is provided a by-pass consisting of a duct 18 having a suction port 19 and communicating through an annular chamber 20 with a suction passage 21 which is extended by a tube 22 to the upper portion of the suction chamber above the level of the fuel therein. This by-pass is also provided with an unregulated vent 23 and with a regulated vent 24. 100 105

To regulate the vent 24, there is provided

the needle valve 25 held in position by the retainer spring 26.

The carburetor is adapted for attachment to an engine manifold, a fragment of which is shown at 27.

The choke valve 2 is fixed on a shaft 28 that is provided at its upper end with a movable stop 29 adapted to engage the stationary stop 30, and provided at its lower end with a lever arm 31 to which may be attached a control wire, not shown, by means of the swivel 32 held by the screw 33. By this means the choke valve may be closed or opened as may be desired for starting and operating the engine.

The constant level fuel chamber is provided with a float 34, which, through the lever 35 and the pivot 36 engages the fuel valve 37 for regulating the height of the fuel in the float chamber. The intake 7 of the fuel passage is at a level amply above the fuel level 38 to avoid tendency to leak. The fuel stands at the same level inside the suction chamber 6 as in the fuel chamber 4 when the carburetor is not in operation.

By locating the orifices 13 at an appropriate height above the bottom of the reservoir, the lower portion of the fuel passage including the reservoir 9, will, when the carburetor is at rest, contain fuel as shown in Fig. 1, up to the bottom of the orifices 13 as indicated at level 39.

During idling, this retained fuel, shown in Fig. 2, assumes in the lower end of the fuel passage, a level indicated at 40 which is much higher than the top of the reservoir or the fuel level 39 when the engine is at rest.

In operation, the suction from the engine manifold 27 draws air into the air inlet 1 and through the restricted air port 14, these being the only two places where air is admitted, all of which air comes from the same source, viz, air inlet 1, or in case the carburetor is used without external resistance at 1, such as a heater or air cleaner, the port 14 may be supplied directly from the atmosphere without the equalizer tube 15. The air enters the mixing chamber 3 tangentially and is set whirling about the center of the mixing chamber, creating therein a vertical depression about the orifices 13. This depression under all load operation of the carburetor is communicated through the orifices 18, the reservoir 9, the leads 10 of the lower end of the fuel passage 8 to the upper end 7 of the fuel passage, and to the suction chamber 6, where it acts on the surface of the liquid fuel in the suction chamber to cause fuel to flow through the fuel orifice and thence to overflow the top of the fuel passage in proper proportions to make a combustible mixture at all air velocities in the air inlet 1.

When the depression in the vortex cham-

ber is not sufficiently great to raise the fuel to the inlet 7 of the fuel passage which extends above the fuel level 38, the lower end of the passage 8 is sealed by fuel accumulating therein because the inner ends of the leads 10 are below the level of their outer ends and the orifices 13.

During load operation of the carburetor, the depression in the mixing chamber is sufficient to clear the fuel passage of any accumulated fuel so that fuel and some air flows freely therethrough. When the engine is slowing down from load operation to idling, the depression beyond the nearly closed throttle, operating through the suction port 19, the duct 18, annular passage 20, suction tube 21, and extension 22 thereof, applies suction from beyond the throttle to the suction chamber 6, which suction is greater than that produced in the suction chamber 6 by the vortex at low speed, thereby increasing the suction on the fuel orifice 5, and thus increasing the flow of fuel. In effecting this, there takes place a reversal of pressure at the orifices 13 causing a stopping or check of the air flowing from the restricted air port 14 with the fuel through the orifices 13, with a corresponding increase of fuel flow through the fuel orifice 5 and such reversal immediately checks the flow of fuel and causes an accumulation of fuel that fills the reservoir 9, the leads 10 of the fuel passage, and the lower end of the drop pipe 8, to some desired height 40.

This height of fuel in the drop pipe 8 is determined by adjusting the depression in suction chamber 6. The greater the depression, the greater the flow of fuel into the top of the fuel drop pipe 8 and the greater the retardation of flow from the orifices 13. Air and mixture flowing through the open vent 23 acts to greatly reduce the depression in the duct 18 below the depression applied in duct 18 from beyond the throttle; and the adjusting vent 24, when open, acts in a similar manner; but vent 24 may be adjusted by the needle valve 25 and this will control the depression remaining in the by-pass and suction chamber 6, and will determine the height 40 of the accumulated fuel.

During idling the reservoir 9 fills to the top so that the fuel stands therein, being retained by surface tension at the orifices 13 and by the balanced depression in the suction chamber 6, and the operating fuel during idling is drawn over the top 7 of the fuel passage by depression in the suction chamber 6 and is added to such accumulated fuel from which it flows gently out of the orifices 13.

This adjusted height 40 becomes a measure of the suction on the fuel orifice 5 by an action similar to the operation of a siphon.

The improvement in this application consists in the formation of the reservoir 9. In former carburetors of the down flow fuel

feed type, the leads 10 to the lower end of the fuel passage continued straight out to the mixing chamber; and all the accumulated fuel was instantly discharged upon opening 5 the throttle with the result that with some engines there was not enough fuel to give the necessary acceleration; furthermore, when closing the throttle suddenly, if the engine had been running at a high speed, 10 the accumulation would not form a seal quickly enough and hence would not produce the richer mixture for idling, and the motor would die, or quit operating. By the added quantity of fuel provided in the reservoir 15 9, these defects are corrected because the accumulation in the reservoir 9 with a rapidly running motor will close the leads 10 to air flow instantly with a quick accumulation of fuel; and a smooth change of speed from 20 high speed to low speed is accomplished.

Upon opening the throttle from idling, the depression in the vortex chamber and the change of air flow in the suction chamber from the by-pass to the fuel passage causes 25 the fuel in the lower end of the passage 8 to be immediately delivered through the leads 10, the reservoir 9, and the orifices 13 to the main air stream and air will immediately follow up this fuel with the new 30 supply of fuel already started, and further by the delivery of fuel lying between the orifices 13 and the bottom of the reservoir 9. Such fuel will be delivered slowly, for the only means of getting it out during opera- 35 tion of the engine is the depression at the orifices 13 which draws air from the suction chamber 6 to act through the leads 10, across the annular space of the reservoir to the ori- 40 fices 13 acting to deliver the fuel from the reservoir 9; and if the throttle is opened only a little way, the suction is not sufficient to re- 45 move much of the fuel from the reservoir 9; but as the throttle is opened more and more, the action becomes more violent with a grad- 50 ual exhaust of all the fuel lying between the orifices 13 and the bottom of the reservoir 9; thus continuing to add an increment of in- 55 creased fuel for speeding up the engine upon suddenly opening the throttle. This action 60 makes it possible to accelerate an engine rap- 65 idly and smoothly from the low speeds at which speeds it is difficult to accelerate the fuel flow from the fuel orifice as rapidly as the air flow accelerates through the carburetor. It is thus seen that this accumulated 70 fuel is released and delivered to the main air stream under eddying action from the leads in amounts varying with the opening 75 of the throttle and the velocity of the main air stream.

The heavy fractions of the fuel that are thrown on the walls of the mixture chamber 3, finally escape under considerable pressure through the ports 41 into the mixture 80 passage 16. The pressure at which the heavy

fractions of fuel are discharged into the mixture passage may amount to one-half pound per square inch at full load and at such pressures air flowing with the fuel in the mixing chamber causes violent atomization 70 of the fuel passing through the ports 41.

Heretofore with carburetors, when the throttle is closed, and during the period that the engine is slowing down when freed from the clutch, or when the clutch is closed and the automobile is coasting, although the use of fuel in the engine is not required, the suction from the engine manifold continues to draw fuel from the fuel supply chamber and such fuel is ordinarily wasted; in this 80 invention the fuel thus drawn from the fuel supply after closing the throttle, is accumulated and retained for accelerating purposes; hence the economy of operation obtained by this improvement is much in- 85 creased over that of former constructions in which the accelerating fuel is taken as extra fuel direct from the fuel chamber.

From the foregoing it is seen that the reservoir 9 is around the fuel passage and is so 90 constructed that a portion of the accumulated fuel therein will be held out of the direct line of normal fuel flow, and an advantage of such arrangement, and also in having the orifices 13 located above the point of com- 95 munication of the fuel passage with said reservoir, is the practical assurance that when an automotive vehicle, such as an automobile, is standing laterally aslant, as on a crowned road, the seal formed by the accum- 100 ulation of fuel in the reservoir will not be broken under ordinary conditions. In this invention the combined area of the suction port 19 and the unrestricted vent 23 is very 105 large in proportion to the restricted air port 14.

By positioning the port 19 nearer the pivotal axis of throttle 17 than vent 23 and relative to the throttle 17 so that the throttle does not pass port 19 until about quarter load 110 I modify the rate of drop of the depression in duct 18 so that upon slowly opening the throttle there is a gradual reduction during idling of the depression in the chamber 6 instead of a sudden reduction. As the throt- 115 tle is further opened a high velocity is ob- 120 tained through the passage 16 and the ve- 125 locity of the mixture past port 19 and vent 23 is sufficient to cause a depression in duct 18 which is applied in the suction chamber 6, so that with 19 and 23 properly proportioned smooth operation upon opening the throttle may be obtained. With a very lean mixture proportion at one quarter load, the added depression from 19 and 23 will gradually 125 make the mixture richer until at full load with wide open throttle it reaches the maximum power mixture desired under those conditions, while at all intermediate throttle po- 130 sitions the mixture is relatively thin and lean.

in fuel thus producing a control for economy and flexibility by the size and relative position of holes 19 and 23 of the throttle.

My positioning the port 19 closer to the pivotal axis of throttle 17 it is apparent that the control of the depression in chamber 6 may be varied.

The reservoir in this invention is formed by a separable perforated ring 12 and groove 10 formed in the outer periphery of body 11. By this construction the size of the orifices 13 and the jets discharged therethrough as well as the size of the well or reservoir, may be easily and quickly varied.

15 A further advantage gained is that when a thin mixture is used the fuel passage will seal quicker than in constructions heretofore used due to the smaller area at the bottom of the fuel passage in this novel construction.

20 I claim:

1. A carburetor of the character described comprising a suction chamber, a mixing chamber and a constant level chamber; a fuel orifice for supplying fuel to the suction chamber; a drop pipe having an intake end in said suction chamber above the normal level of fuel therein, to conduct fuel from said suction chamber during operation of the carburetor; a reservoir encircling the drop pipe; leads connecting said drop pipe with said reservoir; and orifices in line with said

leads opening from said reservoir into said mixing chamber.

2. A carburetor of the character described comprising a suction chamber, a mixing chamber, and a constant level fuel chamber; a fuel orifice for supplying fuel to the suction chamber; a drop pipe having an intake end in said suction chamber above the normal level of fuel therein to conduct fuel from said suction chamber during operation of the carburetor; a reservoir above the bottom of the drop pipe; leads connecting the bottom of said drop pipe with said reservoir; means connecting said reservoir and with 40 said mixing chamber located above the point of communication of said leads with said reservoir and in line with said leads.

3. In a down-flow fuel feed carburetor, a suction chamber, means to supply fuel to 50 said suction chamber, a body having a drop pipe formed therein; there being in said body, leads connecting said groove and drop pipe; a separable perforated ring mounted on said body and over said groove to form 55 a reservoir to accumulate fuel from said drop pipe at closed throttle.

In testimony whereof, I have hereunto set my hand at Los Angeles, California, this 8th day of April, 1922.

PAUL WILFRED ENSIGN.

in fuel thus producing a control for economy and flexibility by the size and relative position of holes 19 and 23 of the throttle.

My positioning the port 19 closer to the pivotal axis of throttle 17 it is apparent that the control of the depression in chamber 6 may be varied.

The reservoir in this invention is formed by a separable perforated ring 12 and groove 10 formed in the outer periphery of body 11. By this construction the size of the orifices 13 and the jets discharged therethrough as well as the size of the well or reservoir, may be easily and quickly varied.

15 A further advantage gained is that when a thin mixture is used the fuel passage will seal quicker than in constructions heretofore used due to the smaller area at the bottom of the fuel passage in this novel construction.

20 I claim:

1. A carburetor of the character described comprising a suction chamber, a mixing chamber and a constant level chamber; a fuel orifice for supplying fuel to the suction chamber; a drop pipe having an intake end in said suction chamber above the normal level of fuel therein, to conduct fuel from said suction chamber during operation of the carburetor; a reservoir encircling the drop 25 pipe; leads connecting said drop pipe with said reservoir; and orifices in line with said

leads opening from said reservoir into said mixing chamber.

2. A carburetor of the character described comprising a suction chamber, a mixing 35 chamber, and a constant level fuel chamber; a fuel orifice for supplying fuel to the suction chamber; a drop pipe having an intake end in said suction chamber above the normal level of fuel therein to conduct fuel from 40 said suction chamber during operation of the carburetor; a reservoir above the bottom of the drop pipe; leads connecting the bottom of said drop pipe with said reservoir; means connecting said reservoir and with 45 said mixing chamber located above the point of communication of said leads with said reservoir and in line with said leads.

3. In a down-flow fuel feed carburetor, a suction chamber, means to supply fuel to 50 said suction chamber, a body having a drop pipe formed therein; there being in said body, leads connecting said groove and drop pipe; a separable perforated ring mounted 55 on said body and over said groove to form a reservoir to accumulate fuel from said drop pipe at closed throttle.

In testimony whereof, I have hereunto set my hand at Los Angeles, California, this 8th day of April, 1922.
